CLAIM

The ornamental design for a ceiling fan blade, as shown and described.

DESCRIPTION

FIG. 1 is a top perspective view of a ceiling fan blade in the environment of a ceiling fan, showing our new design;

FIG. 2 is a bottom perspective view thereof;

FIG. 3 is a top view thereof;

FIG. 4 is a bottom view thereof; and,

FIG. 5 is a side view thereof.

The broken lines illustrate portions of the ceiling fan that form no part of the claimed design.
